UNITED STATES PATENT OFFICE

165,677

COMBINED TREE LIGHTING SET AND CASE THEREFOR

Stanley I. Batkin, New Rochelle, N. Y.

Application February 12, 1949, Serial No. 815

Term of patent 14 years

(Cl. D80—5)

To all whom it may concern:

Be it known that I, Stanley I. Batkin, a citizen of the United States of America, residing at 47 Taymil Road at New Rochelle, county of Westchester and State of New York, have invented a new, original, and ornamental Design for a Combined Tree Lighting Set and Case Therefor, of which the following is a specification, reference being had to the accompanying drawing forming a part hereof, wherein:

Fig. 1 is a top plan view of a combined tree lighting set and case therefor, showing my new design;

Fig. 2 is a vertical central sectional view on a reduced scale;

Fig. 3 is a fragmentary plan view on a reduced scale of the insertion in a flat state.

I claim:

The ornamental design for a combined tree lighting set and case therefor, as shown.

STANLEY I. BATKIN.
